United States Patent Office

Des. 192,201
Patented Feb. 6, 1962

192,201

COMB

Elmer Cave Rolls, 5576 Alberta St., Vancouver,
British Columbia, Canada

Filed Aug. 14, 1961, Ser. No. 66,320

Term of patent 7 years

(Cl. D86—8)

I claim:

The ornamental design for a comb, as shown.
